UNITED STATES PATENT OFFICE.

CLINTON E. WOODS, OF CHICAGO, ILLINOIS, ASSIGNOR TO THE AMERICAN ELECTRIC VEHICLE COMPANY, OF SAME PLACE.

DESIGN FOR A VEHICLE-FRAME.

SPECIFICATION forming part of Design No. 25,920, dated August 11, 1896.

Application filed June 18, 1896. Serial No. 596,074. Term of patent 14 years.

To all whom it may concern:

Be it known that I, CLINTON E. WOODS, a citizen of the United States, residing at Chicago, in the county of Cook and State of Illinois, have invented a certain new and useful Design for Vehicle-Frames, of which the following is a description.

My invention relates to designs for the frames of running-gear for vehicles, and the following is a specification. It is illustrated in the accompanying drawing.

The leading features of my design are the two ring-shaped parts joined together or in close proximity and connected at one end to a cross-piece by bars placed somewhat in the shape of a triangle. At the other end they are connected to a like bar in any convenient manner. The ring-shaped parts are somewhat oval, but I do not think that this is material and do not wish to be limited to that precise shape, as they may vary, but the form must be such as in the main to leave a somewhat ring-like or ovoidal opening. Each of these ring-like parts is connected by the two

bars, which preferably come together, indicated at the forward bar, whereby the two sets of bars are connected. This makes a sort of triangular attachment to the ring-like part.

A is a ring-like part, as shown, slightly ovoidal, though its precise configuration is not material, being generally what I have described by the word "ring-like." From the two extremities of each ring project two bars, which come together at a distant point and thus form a sort of triangle. These two sets of bars are then connected by a cross-bar. From the other side of the ring project bars which may be placed in any manner, my design having special reference to the two ring-like parts and the two triangular parts.

I claim—

The design for a vehicle-frame substantially as shown and described.

CLINTON E. WOODS.
